UNITED STATES PATENT OFFICE

115,347

DESIGN FOR A HIGHWAY VEHICLE

Edmund G. Mathauer, Philadelphia, Pa., assignor to American Car and Foundry Motors Company, New York, N. Y., a corporation of Delaware

Application July 7, 1938, Serial No. 78,338

Term of patent 7 years

To all whom it may concern:

Be it known that I, Edmund G. Mathauer, a citizen of the United States, residing in Philadelphia, county of Philadelphia, State of Pennsylvania, have invented a certain new, original, and ornamental Design for a Highway Vehicle, of which the following is a specification, reference being had to the accompanying drawings, forming a part thereof and in which:

Figure 1 is a side elevational view of the highway vehicle;

Fig. 2 is a front end elevational view of the vehicle and showing in particular the front fender and ventilator arrangement, and

Fig. 3 is a rear end elevational view of the vehicle showing clearly the arrangement of rear doors or removable panels.

The dominant feature of my design consists in the form and contour of the shell of the vehicle and particularly in the form and contour of the ends thereof. The opposite side of the bus is similar to that shown in Fig. 1 with the exception that no door is provided therein.

I claim:

The ornamental design for a highway vehicle, substantially as shown and described.

EDMUND G. MATHAUER.
